Primary Examiner — Cynthia Ramirez(74) *Attorney, Agent, or Firm* — Patricia M. Costanzo, Esq.(57) **CLAIM**

The ornamental design for a tiltable lockable elevating pedestal, as shown and described.

DESCRIPTION

FIG. 1 is a perspective top end view of a tiltable lockable elevating pedestal showing our new design;

FIG. 2 is a perspective bottom view thereof;

FIG. 3 is a top plan view thereof;

FIG. 4 is a bottom plan view thereof;

FIG. 5 is an elevation view of one side thereof;

FIG. 6 is an elevation view of the other side thereof;

FIG. 7 is a perspective top view of an alternate embodiment showing a shorter center, the other areas of the pedestal being as shown in the embodiment of FIG. 1;

FIG. 8 is a perspective bottom view thereof, the other areas of the pedestal being as shown in the embodiment of FIG. 1; and,

FIG. 9 is an elevation side view of the embodiment of FIG. 1 in use.
